United States Patent Office

Des. 195,129
Patented Apr. 30, 1963

195,129

SIDE MOUNTING TELEPHONE SET

Henry Dreyfuss, South Pasadena, Calif., and Harold W. Herrington, Upper Montclair, and Thomas Logan, Plainfield, N.J., assignors to Bell Telephone Laboratories, Incorporated, New York, N.Y., a corporation of New York

Filed Mar. 19, 1962, Ser. No. 69,332

Term of patent 14 years

(Cl. D26—14)

F/G. 1

FIG. 1 is a perspective view of a side mounting telephone set, showing our new design;

FIG. 2 is a front elevational view of a side mounting telephone set showing our new design; and

FIG. 3 is a side elevational view of a side mounting telephone set showing our new design.

The dominant features of our design reside in the portion shown in solid lines on the drawing.

We claim:

The ornamental design for a side mounting telephone set, as shown and described.
